FURNACE CONSTRUCTION

John C. Cameron and Charles E. R. West,
Detroit, Mich.

Application July 1, 1931, Serial No. 548,158

10 Claims. (Cl. 158—1)

This invention relates to heating systems for buildings and it has particular relation to that type of system in which heat is generated in a furnace at a point relatively remote from the zone which is to be heated and is then conducted to the latter point through the agency of a fluid conduction agency which absorbs heat from the furnace and then releases it at the point where it is to be used.

10 The invention has for its main objects the provision of a furnace structure in which a minimum amount of air is sufficient to oxidize the fuel and thus to render its heat energy available, thus obviating the heating of excessive volumes 15 of air in the combustion chamber; the provision of a furnace structure which is adapted to absorb considerable proportions of the heat present in the combustion gases that normally escape through the furnace stacks and then release this 20 heat to the furnace walls; the provision of a furnace structure embodying means for preventing the escape of absorbed heat from the interior of the fire box through convection while the furnace burner is inoperative; the provision of a 25 furnace structure embodying means for simultaneously rendering the burner inoperative and for sealing the fire box of the furnace against convection losses.

The conventional furnace as ordinarily constructed embodies an inner shell or fire box and an outer shell or casing which provides a chamber about the fire box through which a convection medium such as air or water may be circulated for purposes of transferring heat from the walls 30 of the fire box to the rooms or buildings which are to be heated. The walls of the furnace may be supplied with heat by means of a suitable burner disposed in the fire box and which may be fed with fluid fuel such as fuel oil or gas. In 35 these conventional types of furnace the chamber constituting the fire box is substantially unobstructed and mixtures of fuel and air together with the combustion gases generated therefrom flow with but slight turbulence directly through 40 the fire box and out at the chimney. As a result, interaction between the fuel and oxygen of the air to generate heat takes place at a relatively low rate and the amount of radiant heat liberated thereby to the furnace walls is comparatively low. It will also be apparent that in 45 such structures complete combustion does not take place until the mixture of fuel and air has progressed a considerable distance through the fire box and into the stacks. As a result, the temperatures of the combustion gases in the lower

and intermediate zones of the furnace are comparatively low while the temperatures at the zone adjacent to the stack are comparatively high. Under such conditions the combustion gases when under optimum conditions for transferring heat to the furnace walls are in contact with the latter only for a comparatively short period of time. Consequently, only a small portion of the total heat generated by the combustion gases is transmitted to the walls of the furnace and from the latter to the convection medium employed for conveying heat to the buildings which are to be heated.

Furthermore, in the conventional type of furnace structure, the walls of the fire box are comparatively thin and as a result they are very quickly heated to relatively high temperatures. However, since the mass of the walls is relatively low the total amount of heat absorbed is also quite low. Therefore, when the temperature of the 10 room has been raised to a desired point and the burner is shut down the heat contained in the furnace walls is soon dissipated to the convection medium and in order to maintain the temperature, operation of the burner must soon be re-initiated. These undesirable conditions are intensified by reason of the fact that much of the heat absorbed by the furnace walls and entrapped in the combustion gases within the furnace when the burner is closed down is permitted to escape directly up the stacks by reason of convection and is not absorbed by the walls and then re-transferred to the convection medium in the outer chamber.

This invention contemplates the provision of a furnace structure in which these various undesirable effects are overcome by the provision of a foraminous checkerwork like structure in the fire box of the furnace adapted to throw the mixture of fuel and air into violent turbulence and thus obtain substantially complete combustion of mixture at very high temperatures in the lower zones of the furnace, the structure further being adapted to act as a baffle to prevent the direct flow of gases within the fire box through the 15 stack. The invention also includes a damper structure operated in synchronism with the burner structure for substantially completely closing the stack passage when the burner is inoperative and thus preventing convection losses 20 of the heat contained in the products of combustion which may remain in the furnace and also preventing loss through the stack of heat units absorbed in the foraminous structure previously referred to.

For a better understanding of our invention, reference may now be had to the accompanying drawings attached hereto and forming a part of the present specification.

5 Fig. 1 is an elevational view of a furnace structure embodying the principles of the invention in which certain parts are broken away in order to more clearly so disclose details of construction.

10 Fig. 2 is a cross-sectional view taken substantially upon the line 2—2 of Fig. 1.

Fig. 3 is a cross-sectional view taken substantially upon the line 3—3 of Fig. 1.

15 Fig. 4 is a cross-sectional view of a heater coil adapted to be employed in connection with my improved furnace structure for purposes of supplying hot water for domestic use.

20 Fig. 5 is a diagrammatical view of a furnace structure and the electrical wiring employed for controlling the operation thereof.

25 Fig. 6 is a fragmentary cross-sectional view disclosing a slightly modified type of burner structure which may be employed in combination with the baffle structure constituting a portion of the subject matter of the present invention.

30 Fig. 7 is a fragmentary cross sectional view of a damper which may be employed in the stack of the furnace constructed in accordance with the provisions of the present invention, taken on line 7—7 of Fig. 8.

Fig. 8 is a fragmentary view partially in cross-section and partially in elevation of the damper construction disclosed in Fig. 7.

35 The features constituting the subject matter of the present invention may be employed in combination with a furnace 10 of conventional design embodying an outer shell or jacket 11 and an inner shell or jacket 12 between which a space 14 for a convection medium such as water is defined. The inner of these jackets which constitutes a fire box is also so formed as to provide a water head 16 and a steam head 18 through which flues 20 and 22 leading to a stack 24 respectively extend. Conventional pipes (not shown) lead from the steam head 18 to a room 28 indicated conventionally in Fig. 5.

40 The above described furnace structure is supported upon a base 30 having an inwardly directed flange 32 which supports a baffle structure 50 constituting an important element of the present invention and which is to be later described. A burner 34 for fluid fuel is disposed approximately centrally of the base 30 and is adapted to discharge a burning mixture of air and oil outwardly and upwardly into the fire box defined by the walls 12. Fuel oil and air may conveniently be supplied to the burner by means of a conduit 36. Since the structure of the burner is conventional it is not deemed necessary to describe it 55 in detail. It is deemed sufficient to state that fuel and air under the desired degree of pressure is fed thereto through the conduit 36 by means of a motor driven pump structure indicated at 38 in Fig. 5.

60 The baffle or checkerwork construction constituting an important element of the invention comprises a series of upwardly and radially inclined supports 40 of heat resistant material such as cast iron, having feet 42 at their lower end 70 which rest upon the flange 32 and which if desired may be secured in position by a suitable heat resistant cement, not shown. The supports are confined from radial outward displacement by means of a ring 44 surrounding the standards 75 40 in a plane intermediate the ends thereof and

engaging shoulders 46 formed on the outer edges thereof. At their upper ends the standards 40 are slotted as indicated at 47 to receive the outer edge of a circular baffle plate 48, which is adapted to support and thus prevent inward displacement of the upper ends of the supports. In order to protect this baffle plate from excessive heat, a flame guard 50 is secured to the lower surface thereof by means of screws 52 best shown in Fig. 4.

5 The checkerwork structure includes a base ring 54 composed of segments 55 which as shown in Fig. 1 are of inverted trapezoidal cross sectional contour. A cylindrical ring 58 is disposed adjacent to the inner periphery of the wall 12 and rests at its lower edge upon the upper face of the 10 base ring 54.

15 The upper faces of the rings 44 and 58 respectively support the inner and outer ends of a series of laterally spaced fire bricks 60 of trapezoidal elevational contour which are disposed in radial relation with respect to the inner walls of the furnace in much the same manner as the bricks 66 shown best in Fig. 2 and more fully described later. These bricks in turn support a pair of concentrically disposed spaced rings 62 and 64 which, 20 like the ring 54 previously referred to, are composed of a plurality of segments. The rings in turn support a series of radially arranged bricks 66 which, as shown in Fig. 2, when viewed from above are of substantially trapezoidal contour. 25 These bricks, as shown in Fig. 1, are notched at 68 and the ends thereof rest upon the upper extremities of the supports 40. In order to supplement the checker work action produced by this series of bricks a second series of bricks 70 which 30 preferably are of square cross-sectional contour are disposed between the bricks 66 and the ends thereof rest upon the upper faces of the rings 62 and 64. Bricks 66 and 70 support concentrically 35 spaced rings 72, 74 and 76 the outer periphery 40 of the latter of which is disposed adjacent to the inner surface of the wall 12.

45 The checkerwork may be completed by a final series of radially disposed bricks 78 and 80 the former of which, like the bricks 66, are of trapezoidal cross-sectional contour and the latter of which, like the bricks 70, are substantially rectangular. These bricks preferably are arranged in staggered relation with respect to the bricks 66 and 70 in order more effectively to deflect the 50 gases in their upward flow through the furnace.

55 A damper structure preferably is disposed in the stack 24 and may, as shown in Figs. 7 and 8, include a pair of concentrically disposed cylinders 82 and 84 which are disposed transversely of the stack and which respectively include slots 86 and 88 which may be brought into alignment with each other or disposed in staggered relation depending upon the desired operation of the furnace whereby selectively to permit the flow of 60 combustion gases to the stacks or to interrupt the flow in accordance with the temperature existing in the room or building 28. The cylinder 84 preferably is non-rotatably secured in the flue or stack as by welding along diametrically opposite points of tangency 85 and the cylinder 82 is rotatably mounted therein upon transversely extending bars 90 which are rigidly fixed upon stub shafts 92 and 94. These shafts are journaled in 65 bearings 96 and 98 in the side of the stack.

70 For purposes of rotating the cylinder 82 and thus bringing the slots 86 and 88 into and out of register with respect to each other, a lever or arm 100 is rigidly secured to the shaft 94 and the lower end thereof is pivoted to a piston rod 75

102 that may constitute a reciprocable armature within a solenoid coil 104 of conventional construction. This solenoid is provided with attaching lugs 106 which are secured to the side of the stack 24 by means of bolts 108. Energizing current is supplied to the solenoid by means of conductors 110 and 112. When the solenoid is de-energized, the rod 102 is held in retracted position by means of a coiled spring 113 secured to the side 10 of the flue 24.

As best shown in Fig. 5, the winding of solenoid 104 is connected in series with a thermostatically controlled switch 116, disposed in room 28, and is cut into one line 118 of the current supply line for the driving motor of the pump 38. Thus, one supply line 120 is connected to one side of a winding of the motor for pump 38, the other line 118 connected to one side of switch 116, a conductor 112 connects the other side of switch 20 116 to one terminal of the winding of solenoid 104, and conductor 110 connects the other terminal of winding of solenoid 104 to the other side of the winding of the driving motor for the pump 38.

The operation of the above described structure 25 may be outlined as follows: It will be assumed that the temperature of the room 28 is below a pre-determined value and that the supply pump 38 is either operating at a very low rate of speed or else is entirely stopped and the damper structure 30 is closed. Under these conditions the switch 116 will move to closed position thus closing the circuit of the motor 38 and energizing the solenoid 104 to rotate the cylinder 82 in such manner as to bring the slots 86 and 88 into register with 35 each other, thus establishing a draft through the furnace. Under these conditions the burner 34 will operate at full force and the flames therefrom will be directed upwardly and outwardly over the lip of the ring 54 and into the various passageways provided in the checkerwork disposed within 40 the fire box 12. The various units constituting the checkerwork will break up the flow of the mixture of fuel and air and as a result the latter will be thrown into comparatively violent agitation or turbulence, thus thoroughly intermixing 45 the fuel and the air and insuring immediate and complete combustion of the mixture in the lower zones of the furnace. Obviously, a portion of the heat thus generated will be radiated immediately 50 to the walls of the furnace, while a portion will be absorbed by the checkerwork as the mixture flows upwardly through the latter. By reason of the fact that combustion takes place more completely in the lower zones of the furnace than 55 in the conventional structure it will be apparent that the gases at their maximum temperatures will be maintained in the furnace for a much longer period than in the conventional construction and accordingly a higher percentage of heat 60 is absorbed from the burnt gases than in the ordinary furnaces. The checkerwork which includes the baffle plate 48 as an element also extends completely across the stream of gases as it flows upwardly through the furnace and as a result, 65 much heat contained in the central zone, which ordinarily would pass out through the stack, is absorbed. This heat is released to the wall 12 and is thus made available to the convection medium in the chamber 14. After the temperature 70 of the furnace has been raised sufficiently to cause the elevation of the temperature of the room 28 to the desired point, the switch 116 will open and as a result the solenoid 104 will be de-energized and the burner 34 will shut down. De-energization of the solenoid 104 allows spring 113

to rotate the cylinder 82 to bring the slots 86 and 88 into staggered relation thus closing the stack of the furnace. In order to prevent the development of pressure within the fire box 12 which might result in the expulsion of highly heated gases from the furnace into the room in which the furnace is disposed a bleeder bypass 5 including a conduit 122 having openings 124 and 126 disposed upon opposite sides of the damper structure is connected to the flue 24. The size 10 of this bypass of course is such that only relatively small volumes of gases can pass up the stack. Under these conditions convection of heat absorbed by the checkerwork and the furnace wall is substantially prevented. As a result 15 all of the heat absorbed in the latter elements is radiated to the convection medium contained in the chamber 14 and from the latter is conducted into the room 28. By reason of the relatively great quantity of heat absorbed in the system 20 and the prevention of the convection thereof through the sides, the room is maintained at a substantially uniform temperature over a relatively long period of time without the operation of the burner 34. An additional economy of fuel 25 is thus obtained.

In Fig. 6 is disclosed a slightly modified form of our invention which is adapted for use of a burner 130 of the spinner type which includes a rotor 132 driven by a motor 134. Fuel oil may 30 be supplied to the rotor through a passage, (not shown) formed in the rotor shaft 136 or in any other convenient manner. The oil is discharged outwardly between a series of vanes 138 provided upon the upper surface of the rotor. An annular 35 disc 140 is disposed about the rotor and is supported upon flange 32 to prevent the passage of fuel and air downwardly into the base of the furnace structure. The upper margin of this disc 140 is provided with a ring member 142 comprising upwardly extending flanges 144 and 146. These flanges are formed with slots 148 that function more effectively to intermingle the fuel and the air as they are thrown by centrifugal force 40 from the rotor 130. The checkerwork including 45 feet 42 rests directly upon these flanges. The operation of this embodiment of the invention is substantially similar to that disclosed in the previously described figures.

In Fig. 4 is disclosed a water heater structure 50 which may conveniently be employed in combination with the previously described checkerwork and it is highly desirable where the invention is used in combination with furnaces employing air as a convection medium. This heater structure includes inner and outer coils 150 and 152 which are connected with each other in conventional manner and which also are connected to inlet and outlet conduits 156 and 158. These coils preferably are disposed directly above the 55 baffle plate 48 and may be disposed within the circumference of the ring 72 disclosed in Fig. 1.

It will thus be apparent that we have provided a simple and convenient structure for use in connection with conventional furnaces, the use of 60 which results in the more efficient burning of fuel and the more effective transfer of heat of combustion products to the convection medium. The construction is economical to produce and may be employed in combination with substantially 65 any of the standard furnaces. By the use of the refractory checkerwork described a more complete burning of the fuel is obtained, a more compact structure is provided than in structures heretofore provided without materially restrict- 70 75

ing the free flow of gases therethrough, and a more efficient absorption of the heat by the refractory results without disadvantageously affecting the desired heat transmitting effects directly from the gases to the surrounding walls of the chamber as in constructions previously suggested.

Although we have described and illustrated only the preferred embodiments of the invention, it is to be understood that the latter is not so limited but that various modifications may be made therein without departure from the spirit of the appended claims.

We claim:

1. A furnace checkerwork comprising a plurality of vertically spaced refractory rings, a plurality of spaced refractory blocks interposed between adjacent rings, and means for supporting said rings and blocks to form a conical chamber therein.

2. A furnace checkerwork comprising a plurality of series of refractory rings disposed in vertically spaced planes, spaced refractory bricks disposed between each said series and that one of said series next above it, said rings and bricks defining a conical chamber therein, and means for supporting said rings and bricks.

3. A furnace checkerwork comprising a plurality of series of refractory rings disposed in vertically spaced planes, spaced refractory bricks disposed between each said series and that one of said series next above it, said rings and bricks defining a conical chamber therein, inwardly and upwardly inclined supports in said chamber for said bricks, and a transversely disposed baffle plate disposed at the upper ends of said supports.

4. For use between the inlet and the outlet of a furnace, an open checkerwork of refractory material forming a conically shaped chamber therein, a standard in said chamber comprising a plurality of legs converging in the direction of the outlet end thereof, and baffling means supported at the converging ends of said legs and disposed transversely of the path of travel of combustion gases flowing through said chamber.

5. A checkerwork structure for use in a furnace including a plurality of vertically spaced rings of refractory material adapted for contact with the walls of said furnace and interposed spaced blocks of refractory material separating said rings, said rings and blocks cooperating to form a generally conically shaped chamber therein, and upwardly and inwardly inclined standards within said chamber supporting the inner ends of at least a portion of said blocks, those blocks supported by said standards being adapted to slide upwardly thereon under the influence of radial expansive pressure set up therein due to increase in temperature thereof.

6. A furnace checkerwork comprising a series of axially aligned refractory rings disposed in vertically spaced groups, spaced refractory bricks disposed between each said series and that one of

said series next above it, said rings in said series above the lowermost series being supported on said bricks therebelow, and means for supporting the inner ends of said bricks comprising supporting members each having a supporting surface tapering outwardly and downwardly with respect to the axes of said rings whereby upon expansion of said bricks radially of said rings the inner ends of said bricks may be forced upwardly on said supporting surfaces to relieve compressive stresses in said bricks as a result of said expansion.

7. A checkerwork for use between the inlet and outlet of a furnace comprising spaced series of refractory rings and alternate spaced series of refractory blocks, said blocks being arranged radially of said rings and in spaced relation to each other, the number of refractory elements in said series progressively increasing from the inlet end toward the outlet end of said checkerwork whereby the heat absorbing capacity of said checkerwork progressively increases from said inlet end toward said outlet end.

8. A checkerwork for use between the inlet and the outlet of a furnace comprising vertically spaced series of refractory rings and alternate vertically spaced series of refractory blocks, said blocks being arranged radially of said rings and in spaced relation to each other, the length of said blocks in said series of blocks increasing from the inlet end of said checkerwork toward the outlet end thereof whereby to progressively increase the baffling effect of said checkerwork from said inlet end toward said outlet end.

9. A checkerwork for use between the inlet and the outlet of a furnace, comprising vertically spaced series of refractory rings and alternate vertically spaced series of refractory blocks, said blocks being arranged radially of said rings and in spaced relation to each other, the number of rings in said series of rings increasing from the inlet end thereof toward the outlet end thereof whereby to provide a checkerwork progressively increasing in heat absorbing capacity from the inlet end thereof toward the outlet end thereof.

10. A checkerwork for use between the inlet and the outlet of a furnace, comprising vertically spaced series of refractory rings and alternate vertically spaced series of refractory blocks, said blocks being arranged radially with respect to said rings in spaced relation to each other, the number of rings in each of said series of rings increasing from the inlet end of said checkerwork towards the outlet end thereof, and the rings of any one of said series of rings being arranged in spaced and concentric relation with respect to each other whereby to provide a checkerwork progressively increasing in heat absorbing capacity and baffling effect from the inlet end thereof toward the outlet end thereof.

JOHN C. CAMERON.
CHARLES E. R. WEST.
